UNITED STATES PATENT OFFICE.

PAUL C. WITHROW, OF DENVER, COLORADO.

TRUCK FOR RAILROAD VEHICLES.

Application filed October 1, 1923. Serial No. 665,980.

To all whom it may concern:

Be it known that I, PAUL C. WITHROW, a citizen of the United States, and a resident of Denver, in the county of Denver and 5 State of Colorado, have invented a certain new and useful Improvement in Trucks for Railroad Vehicles, of which improvement the following is a specification.

My invention relates to trucks for railroad 10 vehicles of the class or type in which lateral resistance devices are provided, and is an improvement on that for which Letters Patent of the United States No. 1,060,222, were granted and issued to W. E. Woodard, under date of April 29, 1913.

The object of my invention is to provide 15 means, of simple and inexpensive construction, and ready applicability in trucks of the class to which it relates, whereby the movement of the swing bolster, while positively coincident with that of the supporting rockers, shall be rendered perfectly free in a vertical direction.

The improvement claimed is hereinafter 20 fully set forth.

In the accompanying drawings: Figure 1 is a vertical transverse section through a four wheeled locomotive truck, illustrating an application of my invention therein; Fig. 20 2, a partial similar section, on an enlarged scale; Fig. 3, a horizontal section, on the line *a a* of Fig. 2; Fig. 4, a side view, in elevation, of a rocker; and, Fig. 5, an enlarged side view of one end thereof, with 35 connecting links in section.

My invention is herein exemplified as applied in a four wheeled locomotive truck of the swing or lateral motion type, in which, as in present practice, a frame, 1, is supported, through the intermediation of 40 springs, 11, on the journal boxes, 4, of axles, 5, on which the truck wheels, 5^a, are secured.

A swing frame or bolster support, 6, extends from one to the other of the side members 45 of the truck frame, to which it is rigidly secured, at its ends. The weight carried by the truck is primarily applied thereto through a floating or swing bolster, 7, which is provided with a centre plate, 7^a, perforated for the passage of a centre pin. The 50 bolster is supported, with the capacity of relative lateral movement, on cam rockers, as hereinafter described.

In the practice of my invention, referring 55 descriptively to the specific embodiment thereof which is herein exemplified, each of

the ends of the bolster, 7, is, as in Letters Patent No. 1,060,222 aforesaid, supported on a rocker, indicated, as a whole, by the reference character, 9. Each of the rockers 60 comprises a body, 9^b, which extends transversely to the bottom, two cam arms, 9^c, projecting upwardly from the ends of the body, and having curved cam faces, and two connection arms, 9^e, similarly projecting from 65 the body, and spaced at short distances from the inner sides of the rocker arms. Journals, 9^d, are formed on the bottoms of the rockers, at each side thereof, each rocker being adapted to swing, in either direction, on 70 one or the other of its journals, in the traverse thereof on inclined bearings, 6^a, formed on the bolster support, 6. Rollers, 9^f, are also mounted on the rockers, concentrically with the journals, 9^d, said rollers 75 traversing, in the swinging movements of the rockers, on the plane surface of the bottom of the bolster support.

Two oppositely inclined bearings, 7^b, extending, in line, transversely to the frame 80 members, 1, are formed in the bottom of the bolster, on each side of the longitudinal central plane of the truck, said bearings being faced with wear plates, 7^c, and being in line with the cam arms, 9^c, of the rockers, on 85 which they are supported. The rockers, 9, are connected, one to the other, by pairs of links, 8, each pair being coupled by pins, 8^a, to the connection arms, 9^e, of the rockers standing in line transversely on the truck, 90 as shown in Figs. 3 and 5. Rollers, 8^b, journalled in the links, 8, abut on arms, 7^d, projecting downwardly from the swing bolster, 7, and fitting between the members of the pairs of links, lateral movement being transmitted, through said arms, from the bolster support to the bolster, and from the bolster to the rockers.

In the operation of a truck in which my invention is applied, lateral movement is 100 imparted to the bolster, from the truck frame and bolster support, through the coincidently swinging rockers, 9, the connecting links, 8, and the arms, 7^d, and the reverse movement of the bolster permitted, 105 without impairing the freedom of vertical movement of the bolster, as the arms, 7^b, thereof, while following the swinging movements of the rockers, slide freely vertically on the rollers, 8^b, of the links.

In the truck set forth in Patent No. 1,060,222, aforesaid, the rockers are coupled

to the swing bolster by links extending in opposite directions, so that the connection of each rocker to the bolster, is effected on the side of the longitudinal central plane of the 5 truck, further from said rocker. This construction has failed to be fully satisfactory in practice, for the reason that the lateral movement of the bolster, causes all points on the rocker to move on a radius struck 10 from the axis of the swinging movement of the rocker, while the bolster moves vertically, due to its inclined bearing on the rocker. The links connecting the rockers to the bolster, while causing the bolster to occupy a 15 fixed relative position, when normally central, do not effect the same relative position, when the bolster has moved laterally, as the link connections of the rocker and bolster have not moved in the same plane. The 20 rocker connection to the link has moved on a radius from the axis of swinging movement, while the bolster connection to the link has moved upwardly, causing a swing in the link and a consequent shortening of its distance 25 between centres, which necessarily results in a slip between the rocker and its bearing on the bolster.

The objectionable result above indicated, is eliminated in the practical operation of 30 my invention, in which each rocker is, as hereinbefore described, provided with two upwardly extending arms, disposed laterally opposite each other, and spaced sufficiently far apart, longitudinally, to provide clearance for the centre pin. The arms of one 35 rocker are, as shown, connected to those opposite on the other rocker, by continuous links, extending from side to side, and carrying rollers, having a vertically slideable contact with downwardly projecting arms on 40 the bottom of the bolster centre plate, so that the movement of the bolster, while positively coincident with the swinging movement of the rockers, is entirely free in a vertical direction.

I claim as my invention and desire to secure by Letters Patent:

1. In a railroad truck, the combination of a frame; a bolster, adapted to traverse laterally relatively thereto; rockers, journalled in bearings on the frame, extending transversely to said bolster, said rockers having oppositely curved cam surfaces, abutting against reversely inclined bearings on the 50 bolster; and connections, directly coupling said rockers one to the other.

2. In a railroad truck, the combination of a frame; a bolster, adapted to traverse laterally relatively thereto; rockers, journalled in 55 bearings on the frame, extending transversely to said bolster, said rockers having oppositely curved cam surfaces, abutting

against reversely inclined bearings on the bolster; connections, directly coupling said rockers one to the other; and connections, coupling the rockers to the bolster with the capacity of free vertical movement of the bolster.

3. In a railroad truck, the combination of a frame; a bolster, adapted to traverse laterally, relatively thereto; rockers, journalled in bearings on the frame, extending transversely to said bolster, said rockers having oppositely curved cam surfaces abutting against reversely inclined bearings on the 70 bolster; and links, directly coupling said rockers one to the other.

4. In a railroad truck, the combination of a frame; a bolster, adapted to traverse laterally relatively thereto; rockers, journalled in bearings on the frame, extending transversely to said bolster, said rockers having oppositely curved cam surfaces, abutting against reversely inclined bearings on the bolster; links, directly coupling said 80 rockers one to the other; and connections, coupling said links to the bolster, with the capacity of free vertical movement of the bolster.

5. In a railroad truck, the combination of a frame; a bolster, adapted to traverse laterally relatively thereto; arms, projecting downwardly from the bolster, in the longitudinal central plane of the truck, and in parallel transverse planes thereof; rockers, journalled in bearings on the frame, extending transversely to said bolster, said rockers having oppositely curved cam surfaces, abutting against reversely inclined bearings on the bolster; and links, directly coupling said 90 rockers one to the other; and providing bearings on which the downwardly projecting arms of the bolster abut, in each direction of its movement, and are free to slide vertically.

6. In a railroad truck, the combination of a frame; a bolster, adapted to traverse laterally relatively thereto; arms, projecting downwardly from the bolster, in the longitudinal central plane of the truck and in parallel transverse planes thereof; rockers, journalled in bearings on the frame, said rockers having oppositely curved cam surfaces, abutting against reversely inclined bearings on the bolster, and intermediate 100 connection arms; links, coupling the connection arms of the rockers; and rollers, journalled in said links and bearing on opposite sides of the bolster arms.
